Dec. 882

Elias Ingraham, of Bristol, Conn:
Letters Patent No. 882. Dated April 14, 1837

The schedule referred to in these Letters Patent, and making part of the same.

To all whom it may concern:

Be it known, that I, Elias Ingraham, of the Town of Bristol, County of Hartford and State of Connecticut, have invented a new and original design for the cases of Table Clocks and time pieces; and I do hereby declare that the following is a full and exact description of the same, reference being had to the accompanying drawing and to the letters of reference marked thereon.

The nature of my invention consists in the square form of the head, with a circular sash to the dial and other corresponding parts of the case.

The Drawing: Fig. 1. is a front view.

Fig. 2. ... side view.

The material of which I construct my clock case as shown in the drawing is composed of wood of any kind that the fancy of the manufacturer may determine.

Fig. 1 and 2. is the pattern of the designs of the case to which I refer in this specification, composed of columns A, and square head pieces or entablature B, with a circular sash C, to the face of the dial plate, and a square or octagon panel D, below the circular sash C. In the interior of the panel D, I form and introduce a suitable fancy enrichment of carved ornamental fret work of a Gothic or other pattern E. This ornament is placed on the glass of the panel as shown in Fig. 1.

The columns A, and the capital of the same I make plain as Fig. 1 and 2.

The sash door and panel is hung to open in the customary manner.

What I claim as my invention and desire to secure by Letters Patent is the design for a clock case as herein described,

2

Des. 882

with a wood circular sash c. to the dial, in combination with the square top case, also the carved enrichment $\mathbb{E}$, on the glass of the tablet, substantially in the manner as herein set forth and described.
